Patented May 18, 1971

220,778

LUMINAIRE

Edward R. Jablonski, South Milwaukee, Wis., and
Giacinto C. D'Ercoli, Park Forest, Ill., assignors to
McGraw-Edison Company, South Milwaukee, Wis.

Filed Jan. 26, 1970, Ser. No. 21,083

Term of patent 14 years

Int. Cl. D26—03
U.S. Cl. D48—31

Fig. 1

Fig. 2

Fig. 3

*Fig. 4**Fig. 5*FIG. 1 is a right side elevational view of a luminaire embodying the subject invention. The left side view, not shown, would appear substantially the same as FIG. 1 but inverted from side to side.

FIG. 2 is a top plan view of the luminaire shown in FIG. 1;

FIG. 3 is an end elevational view taken from the left of FIG. 1;

FIG. 4 is a bottom view of the luminaire shown in FIG. 1; and

FIG. 5 is an end elevational view taken from the right of FIG. 1.

We claim:

The ornamental design for a luminaire, as shown and described.
